CLAIM

The ornamental design for a tampon, as shown and described herein.

DESCRIPTION

FIG. 1 is a top perspective view of a tampon showing our design;

FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and,

FIG. 8 is a bottom plan view thereof.

The break lines shown in FIGS. 1-8 indicate a symbolic break in length. The appearance of any portion between the break lines forms no part of the claimed design.

The broken lines shown in the drawings represent portions of the tampon that form no part of the claimed design.
